UNITED STATES PATENT OFFICE

DUTEE W. FLINT, OF CRANSTON, RHODE ISLAND, ASSIGNOR TO SWINGRITE COMPANY, INC., OF PROVIDENCE, RHODE ISLAND, A CORPORATION OF RHODE ISLAND

SECTIONAL GOLF SHAFT

Application filed September 1, 1926. Serial No. 132,953.

This invention relates to an improved construction of wooden shaft designed more particularly for use in golf clubs; and the object of this invention is to provide a golf club shaft composed of sections of different materials laid side by side, the flexibility of the sections of one material being different from that of the other, whereby a selection of the desired number of sections of varying flexibility may determine the pliability or stiffness of the shaft as is desired.

A further object of this invention is to alternate sections of bamboo and hickory in a built-up sectional shaft in such a manner as 15 to control the stiffness of the shaft.

With these and other objects in view, the invention consists of certain novel features of construction, as will be more fully described, and particularly pointed out in the appended 20 claims.

In the accompanying drawings:

Figure 1 is a perspective view of a golf shaft of the improved construction of this invention with portions broken away.

25 Figure 2 is a sectional end view of the shaft showing alternate sections of hickory and bamboo of the same sizes.

Figure 3 is a perspective view of the bamboo section of the shaft.

30 Figure 4 is a perspective view of the hickory section of the shaft.

Figure 5 shows the alternate sections of different sizes.

Figure 6 shows a cross-section of shaft 35 showing the sections set in still different relation.

It is found in the building of a sectional golf shaft desirable to provide some means in which its flexibility may be nicely determined or calculated within reasonable limits so that 40 the desired stiffness of the different shafts for the different players may be obtained.

Heretofore, one means of regulating the stiffness or pliability of a shaft was to insert 45 a metal rod into the core of the shaft, while in other instances the grain of the wood cut nearest the center or heart of the tree has been placed either near the center or at the outer surface of the shaft to vary its stiffness; but 50 my improved method of accurately determin-

ing or regulating the stiffness of the shaft is to arrange in the shaft certain sections which are stiffer than others and cemented together, these sections of different pliability, side by side in order to vary the pliability and 55 stiffness as is desired; and the following is a detailed description of one means by which these advantageous results may be accomplished:—

With reference to the drawings, 10 designates the shaft of a golf club having a head 11 which may be of wood or metal as is desired, the body of the shaft portion 10 being made up from a plurality of sections 12, each of which are of sector shape to fit closely in 60 contiguous relation throughout their length to form a cylindrical body which may be slightly tapered, end to end as desired and as 65 illustrated in Figure 1. The term sector refers to sections which are geometric sectors or 70 which have been recessed at the apex.

The sections 13 are of bamboo which as is known is relatively stiff or nonyieldable and are formed by splitting a bamboo pole on the desired angle so that the sections are 75 in segmental shape in cross-section to properly fit together to form the desired shaft.

It will be noted that each of the sections 13 or those substantially sector shape do not come to a sharp edge, but have a slightly 80 curved inner edge 14 due to the natural formation of the stock in some instances. The sections 12 are preferably of hickory but may be made of any wood having the desired inherent strength and flexibility and 85 which is much more limber or flexible than bamboo and is more homogeneous in texture. These sections are substantially sector shape in some cases, coming to an edge 15, altho it is not necessary for the purpose of this invention that such be the case.

It is found preferable in varying the stiffness of the club in some instances to arrange the bamboo and hickory sections alternately 90 as illustrated in Figure 2, altho other arrangements might be used. The bamboo sections which are of a thickness less than the radius of the shaft leave a space or opening 16 in the center of the shaft which permits glue to be employed in securing the sec- 100

tions together, which may squeeze out into the center opening and so permit these sections to come into close contact in order to form a perfect joint.

5 This hollow center opening formed by the shape of the bamboo sections also provides a space into which the deeper or more extended edges 15 of the hickory sections may extend if desired to allow the same to properly seat or in which a filler or core (not shown) may be inserted. However, it will be understood that the hickory sections may be of the same cross-sectional area as the bamboo sections for the purpose of this invention. It will also be apparent that the stiffness or pliability of the shaft may be regulated by varying the relative cross-sectional areas of the hickory and bamboo sections as shown in Fig. 5; that is, if greater pliability or flexibility is desired, the bamboo sections will be relatively smaller than the cross-sectional areas of the more flexible hickory sections, and vice versa if a stiffer shaft is desired.

25 From the foregoing it will be seen that I have provided novel means for controlling the stiffness and pliability of a golf shaft which may be varied at will to suit the requirements of each individual player.

30 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A shaft for golf clubs comprising a plurality of segmental sections of different inherent flexibility whereby the flexibility of the shaft may be regulated.

2. A shaft for golf clubs comprising a plurality of segmental sections, the different sections being of different kinds of wood each having different inherent flexibility whereby the resiliency of the shaft may be controlled by choice of the different sections in making up the shaft.

3. A shaft for golf clubs comprising a body having alternating segmental contiguous sections of bamboo and hickory for regulating the flexibility of the shaft.

4. A shaft for golf clubs and the like, comprising a plurality of assembled sectors glued together, certain of said sectors being of bamboo and others of hickory, each sector having the grain of the wood running longitudinally thereof, and the thickness of some of the sectors being slightly less than the radius of the shaft forming a space for the reception of excess glue in assembling whereby the sides only of the adjacent sectors may contact for securing the sectors together.

5. A shaft for golf clubs comprising a plurality of sectors the different sectors being

of different kinds of wood each having different inherent flexibility and having the grain of the wood running longitudinally thereof, the thickness of some of the sectors being slightly less than the radius of the shaft forming a space for the reception of excess glue in assembling whereby the sides only of the adjacent sectors may contact for securing the sectors together.

6. A shaft for golf clubs comprising a series of sections secured together, the adjacent sides of adjacent sections lying in planes passing through the axis of the shaft and having adjacent sections of bamboo and a more homogeneous wood.

7. A shaft for golf clubs comprising a plurality of sections glued or cemented together, the alternate sections comprising bamboo and a more homogeneous wood, the two different woods having adjacent surfaces in planes passing substantially through the axis of the shaft.

8. A shaft for golf clubs having a plurality of sections secured together, adjacent sections being of bamboo and hickory arranged alternately, the two different woods having adjacent surfaces in planes passing substantially through the axis of the shaft.

9. A shaft for golf clubs and the like, comprising a plurality of assembled sections glued together, certain of said sections being of bamboo and others of hickory, each section having the grain of the wood running longitudinally thereof, the sides of each section converging toward the center of the shaft and the thickness of at least one of the sections being less than the radius of the shaft.

In testimony whereof I affix my signature.

DUTEE W. FLINT.
